(57) **CLAIM**

The ornamental design for a tire, as shown and described.

DESCRIPTION

FIG. 1 is a perspective view of the tire of the present application;

FIG. 2 is an enlarged partial perspective view of a portion of the tire shown in FIG. 1; and

FIG. 3 is an enlarged, partial front thereof; and,

FIG. 4 is a perspective view of a tire of the present application that is a wider tire than the tire of FIG. 1 and has the same tread design.

The tire design shown in FIGS. 2 and 3 is repeated over the remaining circumference of the tire. The side views (inside and outside) are the same.
